UNITED STATES PATENT OFFICE.

WILLIAM A. SMITH AND CLARENCE H. DOCKHAM, OF DETROIT, MICHIGAN, ASSIGNEES
TO CHICAGO PNEUMATIC TOOL COMPANY, OF NEW YORK, N. Y., A CORPORATION
OF NEW JERSEY.

PNEUMATIC TOOL.

Application filed June 6, 1921. Serial No. 475,536.

To all whom it may concern:

Be it known that we, WILLIAM A. SMITH and CLARENCE H. DOCKHAM, both citizens of the United States of America, residing at Detroit, in the county of Wayne and State of Michigan, have invented certain new and useful Improvements in Pneumatic Tools, of which the following is a specification, reference being had therein to the accompanying drawings.

The invention relates to pneumatic tools and has more particular reference to the construction of controlling valve therefor, as hereinafter set forth.

15 In the drawings:

Figure 1 is a longitudinal section through the tool in the axial plane of the valve;

Figure 2 is a similar view showing the valve shifted to another position;

20 Figure 3 is a cross-section on line 3-3 of Figure 1;

Figure 4 is a cross-section on line 4-4 of Figure 1;

25 Figure 5 is a cross-section on line 5-5 of Figure 1;

Figures 6 and 7 are longitudinal sections showing the piston at opposite ends of the cylinder and taken respectively on lines 6-6 and 7-7 of Figures 2 and 1.

30 The cylinder A of the tool is provided with a central annular groove B forming an exhaust channel opening through the port C to the atmosphere. D is the piston within the cylinder which is adapted to

35 over-run the exhaust port C, and E is the piston shank engaging the cylinder guide F and impinging against the end of the tool G held therein.

The valve casing is formed by a boss H

40 projecting from one side of the cylinder and having a cylindrical bore extending transversely therethrough. The central portion of this bore is connected to the fluid supply passage I and on one side of this

45 passage is the passage J leading to the outer end of the cylinder and communicating therewith through the port K. On the opposite side of the passage I is a transverse port or passage L extending

50 downward into the cylinder at the opposite end thereof from the port K. The cylindrical bore through the valve casing has a portion M of large diameter extending from the central passage I to one end of the bore

55 and a portion N of smaller diameter ex-

tending from said central passage to the opposite end of the bore. O is a sleeve valve having a portion P for fitting the large diameter portion M of the bore and a portion Q for fitting the small diameter 60 end of said bore. These two portions of the valve are connected by a central portion R of smaller diameter and the whole valve is slidably mounted on a bolt S, which serves to clamp in place the caps T and U 65 for closing the opposite ends of the bore. The cap U has a portion U¹ extending within a cylindrical recess in the small diameter portion Q of the valve and surrounding this portion U¹ the cap is pro- 70 vided with an annular series of exhaust ports U² communicating with the external atmosphere. The cap T has a portion T¹ projecting into the portion P of the valve, but not closely fitting the same, so as to 75 form an annular chamber V. This chamber in one position of the valve is in open communication with a port or passage W which extends to the cylinder A in a position to be sealed by the piston when at the end of 80 its forward stroke. The valve cylinder is provided with annular grooves H¹, H², H³ and H⁴, which are respectively connected to the passages J, I and L and form ports for cooperating with the heads of the valve. 85

In operation, the passage I being connected to a source of fluid under pressure, such as compressed air, and the valve being in the position shown in Fig. 2 with the piston in the position indicated in dotted lines, the 90 compressed air or other fluid will pass through the channel H² and the central portion of the valve chamber into the channel H¹, passage J and the port K to the cylinder and will drive the piston D forward. At the 95 same time a portion of the compressed air will pass through a restricted port X into the annular chamber V within the portion P of the valve, but as this chamber is in communication through the passage W with the forward end of the cylinder, which latter is in free communication with the exhaust channel B, the pressure will not be greatly in excess of atmosphere. Therefore, the valve will be held in the position shown by the 100 differential pressure on the large and small diameter portions P and Q. As soon, however, as the piston D over-rides the exhaust channel B and seals the passage W, pressure will be built up within the channel V by the 105 110

leakage through the restricted port X. This pressure, acting upon the large area end of the valve, will cause the shifting of the valve into the position shown in Fig. 1, where communication between the passages I and J is cut off and communication is established between the passage I and the passage L. The compressed air will therefore flow through the passage L into the cylinder and will exert a pressure upon the piston for returning the same, the pressure on the opposite side being reduced to atmosphere through communication with the exhaust port C. After the piston has over-run the exhaust port, the pressure on the large area end of the valve will be exhausted through the channel W and exhaust port C, which will again cause the shifting of the valve, cutting off communication between the passages I and L and re-establishing communication between the passages I and J. The shifting of the portion Q of the valve will also uncover the channel H⁴, which through the port H⁵ is in communication with the passage L and this opens connection between said passage L and the ports U² opening to the atmosphere. Thus when the piston has again driven forward and over-rides the main exhaust port B, the air remaining in the cylinder in front of the piston will be forced out through the passage L, port H⁵, channel H⁴ and ports U².

The construction as above described is exceedingly simple and can be manufactured at low cost, while the forming of the valve cylinder by a transverse bore and the supporting of the spool valve upon the bolt, which secures the end caps for the valve casing, forms a construction which is very easily assembled.

What we claim as our invention is:

1. In a pneumatic tool, the combination with a piston and a cylinder having a main exhaust port over-run by said piston, of a valve construction comprising a cylindrical casing having portions of different diameters with a pressure supply port intermediate the same, a valve having heads fitting the portions of different diameters and subjected to differential pressure of the fluid supply, a leak passage from the fluid supply to the end of the casing of larger diameter and a passage from said end of the casing to the cylinder in a position to be sealed by the piston while at one end of its stroke and to be in communication with the main exhaust port when said piston is at the opposite end of its stroke, whereby pressure on the large area end of the valve is alternately built up and exhausted.

2. In a pneumatic tool, the combination with a piston and a cylinder having a main exhaust port over-run by said piston, of a valve construction comprising a cylindrical casing having opposite end portions thereof

of different diameters and having a pressure supply port therebetween, a valve provided with heads fitting the portions of different diameters and subjected to the differential pressure of the fluid supply, a leak passage from the fluid supply to the large area end of the casing, an exhaust port for the small area end of the casing and a passage from the large area end to the cylinder located to be sealed by the piston when at one end of its stroke, and to be placed in communication with the main exhaust port when said piston is at the opposite end of its stroke, whereby said valve is shifted by the alternate building up and exhausting of pressure, and passages controlled by said valve leading to the opposite ends of said cylinder alternately placed in communication with said supply port and the main exhaust port.

3. In a pneumatic tool, the combination with a piston and a cylinder having a main exhaust port over-run by said piston, of a valve construction comprising a cylindrical casing having opposite end portions thereof of different diameters and provided with ports and passages leading to opposite ends of the cylinder and with a central fluid supply port, a valve having heads fitting the portions of different diameters and subjected to the differential pressure of the fluid supply, a leak passage from the fluid supply to the end of the valve casing of larger diameter, an exhaust port for the end of the casing of smaller diameter in communication with one of the cylinder leading passages when said valve is in one position, and a passage from the large area end of said casing to said cylinder sealed by said piston when at one end of its stroke and placed in communication with the main exhaust passage when the piston is at the other end of its stroke.

4. In a pneumatic tool, the combination with a piston and a cylinder having a main exhaust port over-run by said piston, of a valve construction comprising a cylindrical casing having opposite end portions thereof of different diameters and provided with ports and connecting passages for leading to the opposite ends of said cylinder, and a central fluid supply port, a valve having head portions fitting said end portions of the cylinder and subjected to the differential pressure of the fluid supply, a passage from the large diameter end of said casing leading to one end of said cylinder in a position to be sealed by said piston while at one end of its stroke and placed in communication with the main exhaust port when said piston is at the opposite end of the stroke, and a bleed port through the large end of said valve, whereby pressure is alternately built up and exhausted at the large end of said casing to shift the valve in opposite directions.

5. In a pneumatic tool, the combination with a piston and a cylinder having a main exhaust port over-run by said piston, of a valve construction comprising a cylindrical casing having opposite end portions thereof of different diameters and provided with ports and connecting passages for leading to the opposite end of said cylinder, a spool valve having portions fitting the portions a bleed port in said valve establishing restricted communication between the source of fluid under pressure and the large diameter end of the valve casing, whereby the pressure acting on the large area end of said valve is alternately built up and exhausted by the reciprocation of said piston and the sealing and unsealing of the passage thereby. 50 55
- 10 of said casing which are of different diameters and controlling said ports and passages, caps for closing the opposite ends of said valve casing, a bolt for clamping said caps passing axially through said casing and 60
- 15 valve and forming a guide for the latter, a passage from the large diameter end of said casing leading to one end of said cylinder in a position to be sealed by the piston while at that end, and a bleed port establishing restricted communication between said 65 large diameter end of the casing and the fluid pressure passage, whereby pressure is alternately built up and exhausted at said large diameter end to effect the shifting of 70 75 the valve.
6. In a pneumatic tool, the combination of a piston and a cylinder therefor having a main exhaust port over-run by the piston, of a valve construction comprising a casing having a transverse bore with portions thereof of different diameters, said bore having annular channels communicating with a source of fluid under pressure, and channels leading to the opposite ends 80 85 of said cylinder, a spool valve within said valve chamber having portions fitting the portions of different diameter thereof, caps for closing the opposite ends of said casing, a bolt for clamping said caps, passing axially through said casing and spool valve, a passage leading from the large diameter end of said valve casing to one end of said cylinder in a position to be sealed by the piston while at said end and to be in communication with the main exhaust port when 90 95 said piston has over-ridden the same, and

In testimony whereof we affix our signatures.

WILLIAM A. SMITH.
CLARENCE H. DOCKHAM.
